UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

ADDRESSING MACHINE.

Application filed May 5, 1926. Serial No. 106,791.

This invention relates to addressing machines of the type wherein individual address plates are employed. The object of the invention is to provide a simple and efficient manually operable device for removing the address plate, whereby it may be readily changed on each cycle of operation. More specifically, the invention is concerned with an addressing mechanism employing the rotary carrier having preferably inking ribbon beneath which the address plate is inserted. My invention provides a simple device for withdrawing the plate from beneath the ribbon to a point where it may be readily grasped by the operator's hand beyond the machine. The invention is hereinafter more fully described and its essential novel characteristics are summarized in the claims.

20 The drawings illustrate a rotary addressing machine of the multigraph type embodying my invention in conjunction with means for printing the body of a circular letter. Fig. 1 is a vertical central section through such type of machine; Fig. 2 is a plan thereof; Fig. 3 is a perspective of a portion of the rotary drum and adapted to carry the address plate; Fig. 4 is a similar view illustrating the action of my discharging device in withdrawing the plate; Fig. 5 is an end view of that portion of the drum; Fig. 6 is a cross section of the corresponding portion of the drum but looking in the opposite direction, as for instance, on the line 6—6 in Fig. 2.

As shown in the drawings, the printing machine proper is of the type of the multigraph and comprises a rotary drum mounted on a shaft 11, journaled in end frame plates 12 and 13 above a roller platen 14 mounted on a shaft 15. Gearing 16 and 17 and an Oldham coupling 18 connect the drum and platen. Any suitable means, as for example a crank 19 is provided for rotating the drum and platen.

I have shown mounted on the drum a means for printing the body of a form letter, such means comprising a blanket 20 (a portion of which is shown in Figs. 2, 3 and 4) stretched about a segment 21 on the drum and having raised overhanging

projections 22 carrying embossed printing strips 23. The segment is shown as a semi-cylinder resting on the end members 28 and 29 of the drum and held in place by a 55 spring hook 24 engaging the shaft 11. An inking ribbon 25 has its ends wound on spools carried between the end members of the drum, such ribbon extending intermediately about the type form. One of 60 these spools is shown at 27 in Fig. 2.

It will be seen that in the construction described, when the drum is rotated, as by means of the crank, paper fed between the drum and platen may be printed by the 65 type characters through the ribbon. The paper may be fed by hand or in some automatic manner as desired.

The body of the drum adjacent one edge of the segment 21 is shown as provided 70 with a pair of longitudinal channels 30, 31 for the reception of the address plate A. This plate may be of the form shown having an arcuate intermediate region with longitudinal overhanging projections a^1 and 75 depressed edge portions a^2 under-curved on themselves for strength. The projections may carry embossed printing strips a . Between the channels 30 and 31 is a portion 32 of the drum providing a support for the 80 intermediate portion of the plate while the two channels accommodate the edge flanges. These channels extend beneath overhanging strips 34 and 35 on the drum which retain the address plate thereon when it is shoved 85 endwise into place.

To enable the plate to pass readily under the ribbon 25, I may employ a bridge 40 extending across the channel and supporting the ribbon adjacent its edge. This bridge, 90 which preferably comprises a flat piece of spring metal curved corresponding to the address plate and having depressed portions resting on the segment, is specifically the invention of Victor H. Kline and covered in 95 an application of his Serial No. 100,246, filed April 7th, 1926. I have shown the bridge with one of the end portions 41 secured to the segment bar 35 and the other end 42 resting on the surface of the blanket 20 100 mounted on the segment. The surface of the platen 14 terminates short of the path

of rotation of the bridge 40 so that such bridge cannot make any impression on the platen.

The address plate may slide into place with sufficient snugness so that it will remain in proper position during the rotation of the drum without special holding means. However, I prefer to provide a spring latch, engaging the outermost end of the plate when it is inserted. Such a latch is shown at 50 in Figs. 1, 3 and 5 and consists preferably of a spring bent around a pin 51 and having an extending portion of inverted U-shape, projecting just above the plane of the plate when the latter is inserted. In inserting the plate, the forward edge engages the crown of the spring and depresses the spring, which thus engages the underside of the plate until the same has been inserted, when the crown, springing up, engages the outer end of the plate, as shown in Fig. 1.

When installed, the plate is almost entirely covered by the inking ribbon 25, as will be apparent from Fig. 2. To enable the plate to be readily removed, I provide the sliding rod 60, mounted in the segment parallel with the plate channels. This rod is preferably rectangular in cross section and occupies a corresponding passageway on the segment bar 35 which may be made in two parts for convenience of construction. The rod 60 has a laterally extending pin 62, projecting into the groove 31 beyond the address plate. A tension spring 64, anchored to the end of the rod, and to a pin 65 projecting from the bar 35, tends to draw the rod 60 to its innermost position. At its outer end, the rod is provided with an upturned lip 68, which furnishes at once a stop limiting the inward movement of the bar and a handle by which the bar may be drawn outwardly.

In operation, the address plate is shoved endwise manually into place beneath the bridge and inking ribbon until it comes to a stop by engaging the pin 62. At the same time, the latch 50 will spring up beyond the outer end of the plate, so that the plate is retained in a desired position for printing in conjunction with a body form.

The machine is now given one rotation to effect the printing. At the completion of such rotation, the operator draws out the rod 60 sufficiently to eject the plate to a distance where it may be readily grasped. In the operation, the operator ordinarily places the thumb of his left hand just at the right of the upturned lip 68 and moves his hand slightly to the left, as illustrated in Fig. 4. This movement, which he is able to perform very quickly, draws out the rod 60 and with it, the address plate, beyond the side of the machine (as indicated by the broken lines A' in Fig. 1), where it may be readily grasped by the same hand, either between

the thumb and first finger or between the fingers as is more convenient. Such partial discharge of the plate constitutes its ejection, as such word, or a similar word is used in the claims hereof.

Experience has demonstrated that with my ejecting device, the addresses of circular letters may be printed with comparative rapidity by a single operator. If an automatic paper feed is employed (such for instance, as illustrated in Patent No. 1,051,726, of H. C. Gammeter), the operator need pay no attention to the paper and accordingly may employ his right hand to operate the crank and rotate the drum and his left hand to install and remove the plates. He can thus make a succession of rapid rotations with momentary pauses, during which the used plate is removed and a fresh one installed. The machine is equally operative, though at somewhat less speed, if the operator, between installing and removing the plate, employs his left hand to feed the paper. In either case however, the operation is much quicker than the typing of addresses by a typewriter machine on printed letters. Moreover the matching of the addresses with the body on this machine is perfect, since both parts of the form are printed by the same kind of characters through the same inking ribbon.

Having thus described my invention, I claim:

1. In an addressing machine, the combination with an address plate, of a support therefor and a coacting platen, of an ejecting device to engage the address plate, said device being provided with means whereby it may be engaged by the hand of the operator and thus moved by such hand to eject the plate.

2. In an addressing machine, the combination, with a set of address plates, a support therefor and a coacting platen, of an ejecting device adapted to engage an address plate which is in position with reference to the platen, said device having a shoulder adapted to be engaged by the operator's finger, whereby it may be moved by the hand of the operator to eject the plate.

3. In an addressing machine the combination with a support for an address plate, of an ejecting device adapted to engage such address plate and be moved to eject it, and a spring adapted to restore said device to its non-ejecting position.

4. In an addressing machine, the combination with a support for an address plate and coacting platen, of an ejecting device adapted to engage the address plate and provided with a shoulder whereby it may be moved by the hand of the operator and a spring adapted to move said device in the opposite direction to its ejecting movement.

5. In an addressing machine, the combi-

- nation with a platen, of means having a guideway for an address plate adapted to be manually positioned to coact with the platen, a member movable parallel with the guideway and having means to engage the address plate and a spring for restoring said member.
6. In an addressing machine, the combination with address plates, of means having a guideway for such address plate one at a time, a bar slideable parallel with the guideway and having means to engage the address plate and said bar having a projection adapted to be engaged by the operator's hand.
7. In an addressing machine, the combination of a support having a guideway for an address plate adapted to be manually positioned therein, a bar slideable parallel with the guideway and having means to engage the far end address plate and said bar having adjacent the other end of the address plate a lip adapted to be engaged by the operator's hand.
8. The combination, with a platen, of means for supporting an address plate in position to coact therewith, an ejecting member having a projection adapted to be engaged by the inner end of the plate, a spring tending to hold said member in its innermost position, said member to be adapted to be manually engaged and drawn outwardly to eject the plate.
9. In an addressing machine, the combination of a rotary drum having a guideway parallel with the drum axis, for an address plate and an ejecting device on the drum adapted to engage the address plate and provide with means whereby it may be moved by the hand of the operator lengthwise of the drum to eject the plate.
10. In combination of a rotary drum, having a recess parallel with the axis, extending from the end of the drum, an address plate adapted to occupy said recess, a bar slidably mounted in the drum parallel with the recess, and means moved by the bar adapted to engage the plate, whereby the bar, when drawn outwardly, may eject the plate.
11. In combination of a rotary drum, having a recess parallel with the axis, extending from the end of the drum, said recess being adapted to receive an address plate, a bar slidably mounted in the drum parallel with the recess, a spring tending to hold the bar in its innermost position, and a lug on the bar adapted to engage the plate, whereby the bar when drawn outwardly may eject the plate.
12. In combination with a rotary drum, having a guideway for a removable address plate, a ribbon extending across the guideway, a plate ejecting member beneath the ribbon, a spring tending to hold the ejecting member in its innermost position, said bar having also a portion projecting beyond the ribbon whereby it may be drawn lengthwise to effect ejection of the plate.
13. In combination with a rotary printing drum, having a guideway for a removable address plate, a ribbon extending across the guideway, a sliding bar mounted parallel with the guideway, a spring tending to hold the bar in its innermost position, said bar having means adapted to engage the address plate, said bar having a lip on its outer end whereby it may be drawn lengthwise to effect the ejection of the plate.
14. In combination with a rotary printing drum, having means for carrying a printing form and a guideway along the edge of the form for a removable address plate, a ribbon extending across the guideway and form, a sliding bar mounted parallel with the guideway, a spring tending to hold the bar in its innermost position, said bar having a lug adapted to engage the inner end of an address plate shoved lengthwise in place, said bar having a lip on its outer end whereby it may be drawn lengthwise to start the ejection of the plate.
15. In an addressing machine, the combination with a support for an address plate and a spring detent adapted to engage one end of the address plate to retain it on the support against inadvertent displacement, of an ejecting device to engage the other end of the address plate and provided with means whereby it may be moved by the hand of the operator.
16. In combination with a platen, of a slideway in which an address plate may be mounted in coaction with the platen, a spring detent adapted to engage the address plate and to prevent its inadvertent displacement, a discharging device, adapted to engage the address plate and providing a means whereby it may be moved outwardly to overcome the resistance of the spring detent and discharge the plate, and a spring tending to restore the discharging mechanism.
17. In combination with a platen, of a slideway in which an address plate may be mounted in coaction with the platen, a spring detent adapted to engage the address plate and to prevent its inadvertent displacement, a bar slidably mounted parallel with the slideway and adapted to engage the inner end of the address plate and provided adjacent its outer end with means whereby it may be moved outwardly to overcome the resistance of the spring latch and discharge the plate.
18. In combination with a set of address plates of a platen a rotary drum having a guideway parallel with its axis in which an address plate may be mounted in position to coact with the platen, a spring detent

adapted to engage the address plate and to prevent its inadvertent displacement, a discharging bar slidably mounted parallel with the guideway and adapted to engage the inner end of the address plate and provided at its outer end with a lip whereby it may be moved outwardly to overcome the resist-

ance of the spring latch and discharge the plate, and a tension spring drawing the bar inwardly. 10

In testimony whereof, I hereunto affix my signature.

HENRY C. OSBORN.
